UNITED STATES PATENT OFFICE.

EDWARD C. M. STAHL, OF YONKERS, NEW YORK, ASSIGNOR TO PITTSBURGH TRANSFORMER COMPANY, A CORPORATION OF PENNSYLVANIA.

POLYPHASE TRANSFORMER.

Application filed January 20, 1922. Serial No. 530,737.

This invention relates to polyphase transformers and particularly to the arrangement of the various parts of the magnetic core with respect to the paths furnished for the magnetic flux linked with the electric circuits.

The polyphase transformer is generally preferable to the use of a plurality of single phase transformers by reason of economy 10 in the cost of material and manufacture and lowered operating expense. In some forms of polyphase transformers, particularly those of the simplest construction the paths furnished for the magnetizing 15 flux of the different phases are neither equal in magnetic reluctance nor symmetrical in their space relation. For this reason there is a loss of efficiency in the core itself and an unbalanced condition in the polyphase 20 magnetic relationship which is reflected into the exciting electric circuits and which results in objectionable variations in the effective value of the exciting current between the various phases, with attendant greater variations 25 in the instantaneous values of exciting currents.

One object of my invention is to produce an efficient polyphase transformer of a simple form of construction capable of economical manufacture. Another object is to provide magnetic paths for the flux from each of the coils which will be so related as to give a substantially balanced relation of the magnetic circuits and have substantially the same magnetic reluctance, even though the core structure is unsymmetrical as to the space relationship between all of the core legs carrying windings. Another object is to produce a polyphase transformer which 35 will not only have low core loss and high efficiency, but also low, balanced and symmetrical phase exciting currents both effective and instantaneous. Other objects and advantages of my invention will be understood by reference to the following description and accompanying drawings illustrating one embodiment thereof, this particular embodiment illustrating a form of a three phase transformer.

Fig. 1 is a face view of a core with the windings diagrammatically indicated; Fig. 2 is an end view; and Fig. 3 is a vertical section on the line $x-x$ of Fig. 1.

The core is built up of laminations and in this instance has three legs AA' , BB' and

CC' in the same plane carrying the usual primary windings indicated at P^1 , P^2 , P^3 of a three-phase circuit and corresponding secondary windings indicated at S^1 , S^2 , S^3 . The three core legs are joined at their upper 60 and lower ends by the sections A , B , C and A' , B' , C' respectively. The upper ends of legs A , A' and C , C' are also independently connected by the section D of the core and their lower ends by section D' , leaving small 65 air spaces E , E' between the outer sections D , D' and the inner sections of the core which join the three legs. Instead of having an air space, a layer of non-magnetic material may if desired be interposed between 70 the connecting sections; but the magnetic separation of the adjoining connecting sections should be sufficiently great to secure the results desired. The width of the face of strips D , D' will be sufficient to cause the magnetic reluctance of the paths A , D , C and A' , D' , C' to approximately equal the reluctance of the paths A , B and A' , B' ; or the strips may be otherwise so proportioned or 75 related to each other as to substantially fulfill this condition. The core will be built 80 up of layers to the desired thickness, the layers being formed of sections cut to suit the preference of the designer as to form and manner of assembling.

Referring to Fig. 1, the magnetic reluctance between the points $A-A'$, $B-B'$ and $C-C'$ is substantially the same. The yoke portions A , B , B , C , A' , B' and B' , C' have substantially the same magnetic reluctance. 85

The paths furnished to the flux created by current in the coil P^1 are A , B , B' , A' and A , D , C , C' , D' , A' . Due to the fact that the legs and yokes traversed by the magnetic flux in each part of the magnetic circuit are 90 respectively substantially equal to each other in magnetic reluctance, it follows that the magnetomotive force gradient is substantially the same in the corresponding parts of both parallel paths. It therefore follows that the points B and C , are at substantially the same magnetomotive force potential due to the influence of coil P^1 alone and consequently there is then no material interchange of flux between them; likewise the points B' , C' are at the same potential. This arrangement of core parts therefore separates the flux, created by the current in winding P^1 , into two parts when it 95 is outside of the leg A , A' and places the 100

105

110

two other legs B B' and C C' in the same magnetic relationship with respect to the leg A A'.

In the same way it may be shown that the flux created by coil P² has the two equal paths B C C' B' and B A A' B' to circulate in, and that there is no interchange of flux between A and C, and A' and C' through A D C and A' D' C', under the influence of coil P². The same condition holds for the two flux paths linked with coil P³, namely C B B' C' and C D A A' D' C'. In this case there is no material interchange of flux between A B and A' B' due to the influence of coil P³.

It is understood that the effect of leakage flux has been neglected and only the flux paths within the magnetic core itself have been described.

20 The net effect of the arrangement when having properly proportioned parts is to produce a polyphase core in which the magnetic relationship between the portions carrying the windings is mutually symmetrical, and in which a balanced interchange of polyphase flux takes place in the same general manner that it does in a polyphase core having space symmetry.

With my improved construction separate paths for the flux are provided between each combination of any two legs, and all individual flux paths pass through at least two windings of different phases.

It will be evident that by use of my invention I produce a polyphase core for static inductive apparatus which gives a symmetrical and balanced magnetic relationship which reacts on the electric circuits to produce balanced electric relationship, even though the core is so arranged that the electric coils are unsymmetrically spaced; also I obtain a polyphase core of strong and relatively simple mechanical construction having correctly balanced polyphase magnetic interactions resulting in high efficiency.

Although I have described my invention with reference to a three phase transformer, it is evident that it may be applied to polyphase transformers of a different number of phases, and connections of the coils forming the electric circuits, may of course be such as to suit the particular requirements without departing from the scope of my invention. It will also be understood that my invention may be embodied in modified forms of construction without departing from the scope thereof.

I claim:

1. A polyphase transformer having a core 60 providing a plurality of balanced magnetic circuits of equal reluctance for the magnetic flux of each of the polyphase circuits, said core being formed of inner and outer legs and core portions connecting said legs,

windings on each of said legs magnetically 65 interlinked with all of the remaining windings, said core connecting portions providing different paths for the magnetic flux passing through an inner leg from the paths provided for the flux passing through and 70 between the outer legs.

2. A transformer having a core formed of inner and outer legs and a connecting portion joining said legs, said connecting portion being formed with a slot spaced 75 from and extending across an end of an inner leg and dividing the connecting portion into an outer and inner part, the outer part being of greater cross section than the inner part.

3. A transformer having a core formed of inner and outer legs and connecting portions joining said legs, said connecting portions being formed with slots spaced from and extending across the ends of an inner 85 leg and dividing the connecting portions into outer and inner parts, the outer parts being of greater cross section than the inner parts.

4. A transformer comprising a core having legs, the distances between one leg and each of two other legs being different and polyphase windings located on separate legs and bounded by substantially the same two parallel planes, said core having portions 95 connecting legs which are near to one another and independent portions connecting legs which are far or distant from one another, all of said portions providing flux paths of substantially the same magnetic 100 reluctance.

5. A core for a polyphase transformer having an inner leg adapted to receive a winding, said core being formed with slots extending across and spaced from the ends 105 of said inner leg.

6. A polyphase transformer comprising a core having legs, the distances between one leg and each of the two other legs being different, and said core having yoke portions 110 joining said one leg with each of the other legs, said yoke portions having substantially the same magnetic reluctance from said one leg to each of said other legs respectively.

7. Stationary induction apparatus comprising a plurality of windings, means for supporting said windings in spaced relation such that the distance between one of said windings and a second winding is different from the distance between the said 120 one winding and a third winding, means forming a magnetic circuit between said one winding and said second winding, and means forming a magnetic circuit of the same magnetic reluctance between the said 125 one winding and the said third winding.
